(57) CLAIM

The ornamental design for a zippered shirt with faux button placket, as shown and described.

DESCRIPTION

FIG. 1 is a front view of a first embodiment of the zippered shirt with faux button placket showing my design thereof;

FIG. 2 is a right front perspective view thereof;

FIG. 3 is a left front perspective view thereof;

FIG. 4 is another front view thereof, showing the shirt partially opened;

FIG. 5 is another right front perspective view thereof, showing the shirt partially opened;

FIG. 6 is another left front perspective view thereof, showing the shirt partially opened;

FIG. 7 is a front view thereof, showing the shirt fully opened;

FIG. 8 is a right perspective view thereof, showing the shirt fully opened;

FIG. 9 is a left perspective view thereof, showing the shirt fully opened;

FIG. 10 is a front view of a second embodiment of the zippered shirt with faux button placket showing my design thereof;

FIG. 11 is a right front perspective view thereof;

FIG. 12 is a left front perspective view thereof;

FIG. 13 is another front view thereof, showing the shirt partially opened;

FIG. 14 is another right front perspective view thereof, showing the shirt partially opened;

FIG. 15 is another left front perspective view thereof, showing the shirt partially opened;

FIG. 16 is a front view thereof, showing the shirt fully opened;

FIG. 17 is a right perspective view thereof, showing the shirt fully opened; and,

FIG. 18 is a left perspective view thereof, showing the shirt fully opened.

FIGS. 1-18 show two embodiments of a zippered shirt with a faux button placket. The broken line showing an outline of the shirt and collar depict unclaimed portions of the zippered shirt with faux button placket that form no part of the claimed design, while the dashed lines along the edge of the placket and inner portion of the collar depict stitching that forms no part of the claimed design.
